3 Claims. (Cl. 137—156.5)

This invention comprises improvements in or relating to deformable diaphragms for pumps and the like. It is an object of the invention to provide a pump which is capable of dealing effectively with acid or other corrosive liquors, even when these have to be pumped against a considerable head, and which avoids the use of glands and other fitments where leakage is liable to occur. One usual method of dealing with acids and the like is by an acid egg but this involves the use of compressed air; another method is to employ a rubber-lined centrifugal pump but this necessitates a gland around the spindle of the pump; pumps working by means of diaphragm or bellows are normally very bulky in relation to their delivery.

According to one feature of the present invention a pump comprises a pumping chamber having a wall which consists of deformable rubber or like material in combination with means to vary the volume of the pumping chamber periodically by alternately contracting and expanding the wall in a direction parallel to its face.

It will be appreciated that the expression "expanding and contracting the wall in a direction parallel to its face" is intended to distinguish from diaphragm pumps in which the rubber diaphragm is deformed substantially at right angles to its face. It is possible for the wall according to this invention to be expanded and contracted parallel to its face by a movement which includes both a component parallel to the face and a component in another direction, so long as the main effect is due to the enlarging and shrinking of the face of the rubber or the like.

Preferably the deformable wall of the pumping chamber is circular in form and is compressible in an axial direction by a reciprocable end plate. The circular wall may be built up from a number of rubber rings resting one upon the other and united by vulcanizing them together into one whole.

Preferably the outer surface of the wall of the pumping chamber is largely restrained from lateral expansion while under compression by uniting the outer wall to metallic rings which are spaced at intervals around the wall outside the pumping chambers.

Under the term "rubber or like material" there is included in this specification any resilient material of a rubbery consistency, especially including synthetic rubber such as "Neoprene," Buna, and admixtures of such materials with rubber.

It is an important feature of the invention that if the pumping chamber is built up from circular rings which enclose the chamber within them and are themselves surrounded by metal restraining rings, when the wall is compressed endwise the rubber is caused to bulge radially inwards by its faculty for lateral expansion while under compression and the net reduction in volume of the chamber is greater than that which corresponds to the displacement of the end plate, thus increasing the delivery of the pump.

It will be observed that in effect the deformable wall is a wall or cylinder which can contract and expand both longitudinally and radially at the same time and according to the present invention constitutes a pressure resisting diaphragm or bellows although it cannot strictly be described as a bellows inasmuch as the wall is not corrugated. This form of diaphragm or partition is not only applicable in a pump for corrosive liquids or gases but can also be applied to other cases, where bellows or diaphragms are commonly employed such as in the manufacture of valves. Acid resistant valves are commonly made with a bellows to permit movement of the valve member requiring a sliding valve-operating rod moving through a stuffing box and the substitution of a deformable wall in accordance with the present invention for the bellows or diaphragm usually employed permits the valve to be used on much higher pressures.

The following is a description by way of example of certain constructions in accordance with the invention reference being made to the accompanying drawings, in which:

Figure 1 is a cross section of pumping chamber and driving mechanism.

Figures 2 and 3 are cross sections of part of the pumping chamber showing details of construction and effect of compression on chamber walls.

Figure 4 is a cross section of a pumping chamber and valves suitable for compressing gases.

A hollow box-like base 15, Figure 1, is provided containing bearings 16 for a crankshaft 17 and an appropriate system of lubrication 18. The crankshaft spans the interior of the base near the bottom thereof and in the upper part of the base there is a central cylindrical guide 19, within which works a trunk crosshead 20 similar to an engine piston. In the crosshead is a gudgeon pin 21 and a connecting rod 22 serves to drive the crosshead 20 from the crankshaft 17.

On the base there is secured a cylindrical pump chamber casing 23 which is flanged at the

top outwardly. On the flange rests a rubber covered intermediate flange 24 belonging to the pump chamber proper 10 and on the intermediate flange 24 there rests a top flange 25 of the body 64, which carries lateral connections for inlet and outlet valves (not shown). Both the interior of the pump body 64 and the lateral connections are rubber-covered.

The pumping chamber, tube or cylinder 10 is supported within the pump chamber casing 23 by the aforesaid intermediate flange 24. This chamber tube or cylinder 10 is built up from a number of superposed rings of India rubber 13 and it is closed at the bottom by a rubber-covered end plate 31. The end plate 31 has a central boss 32 on the side remote from the pump chamber 10 and is connected to the reciprocating crosshead 20 in the base 15 by means of an intermediate compression member 33 which connects the boss 32 and the crosshead 20 with a right and left-hand thread so that the setting can be adjusted. Each of the rubber rings 13 has a cylindrical internal face and parallel top and bottom faces. Each ring 13 is vulcanized to a surrounding steel restraining ring 14, the thickness of which in an axial direction is less than the thickness of the rubber ring and the outer corners of each rubber ring 13 are bevelled as shown at 35, Figures 1 and 2, to suit the thickness of the steel ring. Between each of the rubber rings 13 there is inserted a thin steel washer 34, the outside diameter of which is equal to that of the steel rings 14, and the inside diameter of which is somewhat greater than the inside diameter of the rubber rings 13. This washer 34 is covered with rubber on its inner part where it fits between the rubber rings 13. The whole of this assembly is vulcanised together so that the rubber rings 13 together with the India-rubber which covers the intermediate washers 34 form one uniform internal rubber wall 12 to the pumping chamber 10 which is also united to the rubber-covered intermediate flange 24 at the top and to the rubber-covered end plate 31 at the bottom. One of the purposes of the thin washers 34, which are intermediate between the rubber rings, is to support the rubber during vulcanisation and to this end during the vulcanisation process the washers 34 are packed so that they are equidistantly spaced from the steel rings 14 which are vulcanised to the outside of the rubber rings 13. This packing is done by appropriate metal wedges or shims in the form of split rings which are removed after vulcanisation leaving the washers and the steel rings equally spaced from one another. It will therefore be seen that a considerable amount of end-wise compression can be given to the pumping chamber 10 (which is built up of the rubber rings 13, fused into one continuous external wall to the chamber) before the steel rings 14 have been brought into contact with one another. During compression the rubber forming the chamber is held from expanding outwardly by the steel rings 14 and the intermediate washers 34 but is free to expand inwardly in a lateral direction into the chamber 10. The chamber is therefore not only reduced in volume by the reduction in its length but also by the bulging inwards of the walls, as shown in Figure 3. This two-fold reduction in volume of the pumping chamber 10 is very similar to the action of the alimentary canal of animals and is known in medical circles as "peristalsis."

A further purpose of the steel washers 34 is

to divide the rubber wall 12 of the pumping chamber 10 into a number of separate rings in order to control and equalise distortion of the rubber under compression and also to conduct away heat that may be generated in the substance of the rubber due to rapid compression when the pump is run at high speeds. It is essential that good adhesion be made between these steel rings 34 and the rubber rings 13 in order to produce a continuous wall incapable of separation.

In operation the spacing between the cross-head 20 and the bottom end plate 31 of the pumping chamber 10 is so adjusted that the India-rubber is in slight compression when the crankpin is at the bottom of its stroke. A length of stroke is imparted to the crankpin which may be, say about one-sixth of the length of the pumping chamber 10 and the rubber is compressed to this extent during the upstroke of the cross-head 20, expanding again during the downstroke. Liquid is drawn into the pumping chamber through the inlet valve 26 at the top and fills the chamber during the operation of the pump. When the pump-chamber 10 is quite full liquid is forced out on the upstroke through the outlet valve 27. It will be observed that the whole of the interior of the pumping chamber 10 including the top valve and casing 64 is rubber-lined so that the pump can handle acids or any liquid the rubber is capable of withstanding; also that there is no relative movement of the walls at any point and consequently no glands or packing is necessary. A pump of this description can operate at a fairly high speed of reciprocation; the stress on the reciprocating parts is always in one direction so that backlash between the limits of working does not arise; owing to the steel rings 14 surrounding the rubber pumping chamber 10 it can operate against a high pressure; and owing to the fact that the lateral expansion of the rubber is utilized as well as its direct compression, together with the high speed at which the pump can be worked, the capacity of the pump for a given size is reasonable.

It is necessary to ensure that the rubber pumping chamber 10 when under compression shall maintain itself in a straight line. This is assisted by the crosshead 20 hereinbefore described but it can be further assisted, if desired, by guiding the movement of the external steel rings 14. These may be provided with eyes 36 at several places around their periphery which slide on vertical guide rods 37 mounted parallel to the movement within the pump-chamber casing 23.

It will be appreciated that while one particular form of pump has been described modifications may be readily be made within the scope of the invention.

Figure 4 illustrates a pump suitable for use when dealing with corrosive gases. The rubber-lined pump chamber is built up in two parts. The upper part consists of a rubber-lined metal cylinder 50 having a flange 51 while the lower part of the pump chamber consists of a deformable wall or cylinder built up of rubber rings 13, metal restraining rings 14 and metal washers 24 built up in the manner hereinbefore described, the metal rings 14 being provided with eyes at several places round their periphery and sliding on the vertical guide rods 37. The two halves of the pump chambers are bolted together through the intermediate rubber washers 52. The reciprocable end plate 53 is bolted to an ebonite plunger 54 and moves backwards and forwards therewith

inside the bellows. The plunger is of such a diameter that it nearly fills the space within the bellows when the latter are compressed fully, and thus obviates the clearance space which would otherwise exist in chamber 50 and would prevent the pump from being effective on gases. The top part 50 of the chamber is connected to the inlet passage 57 and the outlet passage 58 through the inlet valve 55 and outlet valve 56 respectively. These may be rubber valves of well known type.

As shown in Figure 4 the plunger is at the end of its suction stroke, the chamber and clearance spaces being then filled with the gas. On the return stroke the plunger 54 moves up to within tolerance limits of the end of the chamber and the gas is driven through the outlet valve 56 and passage 58. During this operation the deformable wall of the pump chamber is compressed as the end plate 53 moves upward with the plunger. On the return stroke of the plunger the inlet valve 55 opens and gas is drawn into the chamber and at the same time the compressible part of the chamber recovers its initial state.

I claim:

1. A deformable tube having a wall which consists of compressible elastic material built up from elastic rings, metal restraining rings surrounding the elastic material at intervals along its length and metal washers embedded in the elastic material in the intervals between the restraining rings in combination with a reciprocable end plate to vary the length of the tube. 30

2. In a pump for corrosive fluids, the combination of a pumping chamber having a circular wall which consists of deformable elastic material, an end plate secured to said wall, means to reciprocate the end plate so as to alternately compress and expand the said wall endwise, restraining rings around said wall partially embedded in the substance of the wall and spaced at intervals along it, and guide-bars extending parallel to the direction of movement of the end plate and engaging each of the restraining rings to cause them to move in a straight line when the said wall is compressed, said wall being encircled by rigid washers at intervals located so as to alternate with the restraining rings.

3. In a pump for corrosive fluids, the combination of a pumping chamber having a circular wall which consists of circular rings of rubber each of which carries a restraining ring around its outer periphery and between which are intercalated metal washers, the whole being vulcanised together, an end plate secured to said wall, means to reciprocate the end plate so as to alternately compress and expand the said wall endwise, and guide-bars extending parallel to the direction of movement of the end plate and engaging each of the restraining rings to cause them to move in a straight line when the said wall is compressed.

NORMAN SWINDIN.
